INVENTOR.
Bernard Golden,
BY Mr. J. H. Campbell,
ATTORNEY

UNITED STATES PATENT OFFICE.

BERNARD GOLDEN, OF NEWARK, NEW JERSEY.

GRAPPLING DEVICE.

Application filed October 22, 1924. Serial No. 745,080.

This invention relates to an improved grappling device that is constructed so as to provide an ease of manipulation so that the jaws or hooks that form the grasping part 5 of the device can be positively operated and also providing for a sounding or testing means that can be used to aid in the finding of solid substances in the bottom of the sea and maintain the device so that it is centrally 10 located over the article to be grasped and raised when the jaws are closed.

The invention is designed for use in salvaging operations and also in construction operations but it is particularly adapted for 15 use at extreme depths where a diver cannot descend and where it is desirable to sound or "feel" the bottom of the sea before the raising operation is attempted.

The invention is further designed to provide not only a sounding weight but one that 20 can also be utilized as a magnetic lift either alone or in conjunction with the jaws.

The invention is illustrated in the accompanying drawing in which Figure 1 is a perspective view of the device suspended from a boat or dredge with the jaws of the grappling mechanism open and Figure 2 is an end view of the grappling device with the 25 jaws closed and lifted from the water.

The grappling device is constructed so as to require three lines and for an easy and convenient operation I use three booms, one of the booms 10 being used for raising and lowering the grappling device and the booms 30 11 and 12 are used for opening the jaws or hooks of the grappling device, these booms being operated in the usual way through suitable winches illustrated only in general outline at 13, the ropes or cables from the 35 booms being passed over suitable rigging on the mast 14. This part of the apparatus is not described in detail since it is of well known form.

The grappling device comprises the jaws 40 15 and 16 which are adapted to be swung apart or close together usually being curved so as to form somewhat of a receptacle when closed and are pivoted as at 17, the extensions 18 being connected by links 19 with the pivot 20 which is suspended from the cable 21 which is the one that passes over the boom 10.

Suitably secured to the outer sides of the 45 jaws 15 and 16 are the ropes or cables 22 and 23 which pass over the booms 11 and 12,

respectively, and are operated to raise the jaws 15 and 16 to open them and, if need be, by proper regulation to assist in raising any very heavy article grasped by the jaws.

Suspended centrally within the jaws when 60 they are closed and preferably from the pivot 17 is a weight 24 which is usually flat on the bottom so as to provide a considerable area of contact although it can be of various shapes and it will be evident that when the weight is exposed by raising the jaws 15 and 16, it is available for use as illustrated in Figure 1 and with trained men operating the device, the weight can be raised and lowered and thus caused to descend at various 65 points on the bottom so that by the "feel" of the weight it can be determined when the device contacts with solid hard objects as differentiated from the usual soft mud at the bottom of the sea.

When a hard object is encountered by the weight the jaws are released by relaxing the lines 22 and 23 and the jaws are closed positively by hauling up on the line 21 which then raises the article grasped to the surface 70 and if it is necessary, the lines 22 and 23 assist in the raising since they will not tend to open the jaws if they are raised at the same speed as the line 21.

The weight 24 can be utilized for assisting in raising metallic objects either alone or in conjunction with the jaws or the weight 24 can be magnetized by electrical connections and a suitable source of current and I indicate the wire 25 as illustrating how the current can be carried down to the weight 24 so that its attraction to objects can be utilized in assisting in the finding of iron or steel articles and at the same time can function as a sounding or testing element 80 as above described.

I claim:

1. A grappling device comprising a pair of jaws hinged together and having extensions beyond the pivot, links hinged together and at their ends to the extensions, means for securing a cable where the links are hinged together, a weight suspended from the pivot of the jaws and lines secured to the jaws for opening them so that they swing 100 above the weight.

2. A grappling device comprising a pair of jaws hinged together so that they approximately abut where closed, extensions on the jaws beyond the pivot, links hinged at their 105 110

ends to the extensions and at their opposite ends to each other, each jaw having a recess for the passage of the extension of the other, 5 links, lines secured to the jaws to open them, and a weight suspended between the jaws and disposed so as to be below the jaws when

they are open and to be between them when they are closed.

In testimony that I claim the foregoing, 10 I have hereto set my hand, this 15th day of October, 1924.

BERNARD GOLDEN.
